ATT'y's.

UNITED STATES PATENT OFFICE.

FRANS ROBERT PÄIVIÖ, OF RAISIO, FINLAND.

INTERCHANGEABLE CONTACT EXTENSION.

Application filed September 28, 1927, Serial No. 222,644, and in Germany April 2, 1927.

This invention relates to interchangeable contact extensions for the pole springs of flash lamp batteries of that type in which both pole springs appear at one end of the 5 battery, one being intended for direct contact with one of the terminals of the incandescent bulb, while the other is intended to make contact with a push button or other type of switch associated with the flash light 10 casing, and which in turn may be manipulated at will to make contact with the other terminal of the incandescent bulb, thereby closing the circuit through said bulb.

Flash lamp batteries of the type indicated 15 are manufactured in such large quantities that there is great chance for imperfections in said batteries passing unnoticed. Particularly, is this true of the pole springs which are frequently found, even in a fresh 20 battery to be laterally deflected through slight defects in their manufacture or assembly so that when placed in the flash lamp casing, such battery fails to make good contact either with the incandescent bulb 25 or with the switch mechanism, so that the flash lamp fails to operate satisfactorily.

The present invention has for its object 30 the provision of auxiliary contact members which may be placed upon the pole springs and which function in such a manner as to avoid failures in the operation of the flash lamp due to inherent defects in the pole springs.

A further object of the invention is to 35 provide contact extensions which may be operably positioned instantly and without the use of tools and which may be interchangeably employed upon fresh batteries, so that one set of contact extensions will out- 40 last any number of batteries.

Still another object of the invention is to 45 provide pole spring extensions of so wide an area as to assure contact with the incandescent bulb or with the switch mechanism regardless of the degree of lateral deflection of the battery pole spring and which at the same time is provided with buffers of insulation material adapted to coact with the sides of the flash light casing, either to correct 50 the lateral bias of the pole spring if it is so great as to normally come into contact with the side of the casing, or to pre-

vent any accidental contact between the conductive part of said extension and the casing in the use of the device. 55

Other objects of the invention will appear as the following description of a preferred embodiment thereof proceeds.

In the drawing in which similar reference characters are used to denote the same 60 element in the several figures,

Figure 1 is a plan view of a flash lamp battery showing one form of my pole spring extension applied thereto.

Figure 2 is a similar view showing another 65 form of pole spring extension.

Figure 3 is a side elevation of flash lamp battery of the type to which the present invention appertains.

Figure 4 is a similar view of the flash 70 lamp battery showing the form of the invention illustrated in Figure 2 applied to one of the pole springs, and that form of the invention illustrated in Figures 5, 6 and 7 applied to the other pole spring. 75

Figures 5, 6 and 7 are respectively an end elevation, a side elevation, and a bottom view of a modified form of the invention particularly adapted to use with the switching mechanism illustrated and described in 80 my companion application No. 1,590,541 granted June 26, 1926.

Referring now in detail to the several figures, the numeral 1 represents a flash lamp battery of well known and conventional construction having the pole springs 2 and 3 projecting from the upper end thereof. Said pole springs are in the form of flat leaf springs angularly disposed, one of said springs being adapted to touch a terminal 90 of the incandescent bulb, not shown, used with the flash lamp and the other to make contact with suitable switching mechanism, not shown, which in turn makes contact with the other terminal of the incandescent 95 bulb when operated.

On account of the enormous quantities in which flash light batteries of this type are produced defective pole springs are commonly encountered, the defects usually consisting of lateral deflection of one or the other of said pole springs so that it does not come up into good contact with the bottom terminal of the incandescent bulb but

sometimes misses the bottom terminal and makes contact with the side terminal. Occasionally, the lateral deflection of the pole spring is so great that when placed in the 5 casing it touches the side thereof and short circuits the battery.

Adverting first to that form of interchangeable contact extension shown in Figure 1, the same consists of a plate 4 of conductive material. The superficial area of 10 this plate is so great that regardless of the amount of lateral deflection on the part of the pole spring to which it is attached, this plate can always be relied upon to make good 15 contact with the terminal of the incandescent bulb and never to slip off to the side of said bulb as frequently occurs with the ordinary narrow pole springs. The contact extension is also provided with a plate 6 of insulation 20 material which in the illustrated embodiment of the invention has the form of a square arranged at 90 degrees displacement to the conductive plate 4 so as to provide corners 10 which project laterally on each 25 side of the extension constituting insulation buffers which prevent accidental contact of the plate 4 or of the pole spring itself with the lateral walls of the flash light casing, not shown, but which are in general, of corresponding shape to that of the battery. In 30 the drawing the front corner of the square is cut off, merely for convenience, this feature being altogether immaterial to the invention.

35 The corners of the conductive plate 4 are bent around so as to underlie the insulation plate 6 as is shown in Figure 1 thus tying the conductive and insulation plates together into a unitary whole and thereby providing 40 a space between said plates within which the end of the pole spring 2 may be slidably forced in the act of mounting said extension upon the pole spring. It is obvious 45 that either one or both of the pole springs 2 or 3 may be provided with a contact extension of this type, that the contact extension so made may be removed or applied to the pole spring without tools and that it may be repeatedly applied to fresh batteries when the batteries are renewed.

50 In that form of the invention illustrated in Figure 2 the extension takes the form of an elongated conductive plate 4' the forward portion of which is widened to afford 55 a wide superficial area for exactly the same purpose as is done in connection with the modification already described. In this case, however, a narrow strip 6' of insulation substance is provided about which the forward end of the conductive plate 4 is angularly bent as shown at 11 in Figure 4, said insulation strip being in this manner unitarily retained by the conductive plate. The insulation strip 6' is of such length as to

65 extend laterally beyond the edges of the conductive plate 4' so as to prevent accidental contact of the conductive plate with the sides of the flash lamp casing.

70 The rearward portion of the conductive plate 4' is provided with lugs 7 as shown in Fig. 7 adapted to be bent about the pole spring 2 forming a socket for retaining the extension upon the pole spring. It will be noted from Figures 1, 2 and 3 that the pole springs are of that type having a downwardly struck projection or teat 9, as shown 75 in Fig. 3. This is made use of in that form of the invention shown in Figure 2 to prevent the contact extension slipping endwise from the pole spring. To accomplish 80 this purpose the lugs 7 are notched, preferably with semicircular notches indicated at 8 in Figure 7, these notches registering with the opposite sides of the teat 9, shown 85 in Fig. 3 together surrounding the same so as to hold the contact extension from longitudinal displacement.

90 Figures 5, 6 and 7 are details and, that form of the invention shown in assembled relation in Figure 4, is particularly adapted 95 as has been stated in the objects of the invention to the switch means described in my companion application No. 1,590,541 granted June 26, 1926. In this form, the end of the contact extension which engages the pole 100 spring is preferably made in exactly the same manner as that described in connection with Figure 2, that is to say, it includes two lugs 7 notched as shown at 8 in Figure 7 and surrounding the teat 9 of the pole spring, as shown in Fig. 3. The active end of the contact extension is preferably bent U-shaped above its socketed end as shown at 5 in Figures 4 and 6 and the extremity of this bent portion is longitudinally slotted so as to 105 form a tongue 5' which is struck up from the main portion 5 of the spring extension in such a manner as to be depressed under compression in the same direction as is the main portion 5.

110 The lugs 7 are preferably notched at their ends as shown in Figure 7, so that the device may be applied to the pole spring by pushing it endwise upon the pole spring, the teat 9 engaging the indentation formed 115 by the notches 8 so as to spread the lug sufficiently to permit the device to be slipped into place, the lugs automatically closing around the teat 9.

120 It is obvious that numerous changes can be made in the detailed construction of the contact extensions as shown and described without departing from the essence of the invention and that the embodiments shown are therefore to be considered by way of example only and not for the purpose of imposing unnecessary limitations to the scope 125 of the invention, the latter being determined

by a liberal construction of the terms of the appended claim.

What I claim is:—

An auxiliary terminal for batteries used
5 in metallic cased flash lamps, having a socketed portion adapted to be removably slipped over the battery terminal, and a buffer of

insulation material carried by said terminal to prevent accidental contact between the casing of the flash lamp and the metallic 10 part of said terminal.

In testimony whereof I have signed my name to this specification.

FRANS ROBERT PÄIVIÖ.
